N. Y., a corporation of Delaware

Application April 4, 1938, Serial No. 199,890
In Germany April 6, 1937

5 Claims. (Cl. 220—9)

This invention relates to refrigerators, and more particularly to refrigerator cabinet structure.

It is an object of the invention to provide an improvement for supporting wall members of a refrigerator cabinet in spaced apart relation, and particularly for supporting an inner liner within and about a door opening of an outer shell of a refrigerator cabinet.

The above and other objects and advantages of the invention will become apparent from the following description taken in connection with the accompanying drawing forming a part of this specification, and of which:

Fig. 1 is a front elevation of a household refrigerator embodying the invention;

Fig. 2 is a sectional view taken in line 2—2 of Fig. 1; and

Fig. 3 is an enlarged fragmentary view, partly broken away and in section, of the door opening shown in Fig. 2 to illustrate details of the cabinet structure more clearly.

Referring to Fig. 1, the invention is embodied in a refrigerator comprising a cabinet 10 having supporting legs 11. The cabinet 10 includes an inner metal shell or liner 12 arranged to be supported within an outer shell 14 and insulated therefrom within any suitable insulating material 15. The liner 12 defines a thermally insulated storage space 16 having an opening and into which access is afforded by a door 17.

A cooling element or evaporator 18 is located in storage space 16, such cooling element being operative to produce a refrigerating effect to freeze ice cubes and maintain the storage space at a desired low temperature.

A horizontal plate 19 is disposed within cabinet 10 and, with a rear panel 20, forms a container within outer shell 14 in which the insulating material 15 is retained in position. The door opening is provided with a trim strip 21 which overlies the edges of the liner 12 and outer shell 14. The door 17 is provided with the usual sealing gasket 22.

In accordance with this invention, improved structure is provided for rigidly supporting inner liner 12 within outer shell 14 about the door opening of the latter. The supporting structure includes a plurality of spacing blocks or members 23 which may be formed of a suitable poor heat conducting material, such as, for example, the material commercially known as Bakelite. The blocks 23 are provided with a threaded opening at each corner thereof, whereby the blocks may be secured by screws 24 and 25 to the flanges

26 and 27, respectively, of the outer shell 14 and inner liner 12. The spacing blocks 23 are spaced apart a suitable distance so that the inner liner 12 will be rigidly supported within the outer shell 14. The number of spacing blocks 23 required to provide a rigid support for inner liner 12 is not very great, and adequate supporting strength may be effected by providing from about three to five blocks per meter, for example, about the periphery of the door opening. 10

In order that trim strip 21 may be rigidly secured in position, the spacing blocks 23 are provided with threaded openings whereby metallic strips 28 may be secured to the blocks by screws 29. The blocks 23 are formed with an integral 15 raised portion 30 to provide a shoulder against which the metallic strips 28 snugly fit. Each metallic strip 28 may extend along a side of the door opening. At the regions where the strips 28 are secured by screws 29 to the spacing blocks 20 23, the strips 28 may be formed with depressed portions, as indicated at 31. The portions 32 of strips 28 between the depressed portions 31 are therefore spaced from the spacing blocks 23.

The metallic strips 28 are provided with openings 33 adapted to receive screws 34 for securing the trim strip 21 in position. The metallic strip 28 serves as a supporting ledge for the trim strip 21. Inasmuch as the spacing blocks 23 are formed of poor heat conducting material, as explained above, the strips 28 may be formed of metal and serve as a supporting ledge so that the trim strip will be rigidly secured in position. The adjacent ends of the trim strips 21 at two sides of the door opening may be connected at 35 the corners by suitable angle members 35.

The spacing blocks 23 are of such shape that the metallic strips 28 are inclined or are at a slant when they are secured in position. When the flat trim strips 21 are fixed in position against the supporting ledge, therefore, they are also inclined about the door opening and slant inward from the point 36 at the outer shell 14 to the point 37 at the inner liner 12. In the embodiment shown, the trim strip 21 bears against the 40 raised portions 32 of the metallic strip 28, the flange 28 of the outer shell 14 at the point 36, and obliquely bears against the flange 27 of inner liner 12 at the point 37.

In place of screws 24, 25, and 29 which are 50 in threaded engagement with openings in spacing block 23, the spacing blocks 23 and metallic strips 28 may be secured in position by bolts adapted to receive threaded lock nuts. This may be readily done since the space beneath flanges

26 and 27 and the rear of spacing blocks 23 is readily accessible from the exterior of the cabinet about the door opening. In place of spacing blocks formed of plastic material, such as Bakelite, blocks formed of wood or any other suitable poor heat conducting material may be employed.

While a single embodiment of the invention has been shown and described, such modifications 10 and variations are contemplated as fall within the true spirit and scope of the invention, as pointed out in the following claims.

What is claimed is:

1. Refrigerator cabinet structure including inner and outer metal walls spaced apart to form heat insulation space therebetween, a plurality of pieces of a resinous product located at intervals between the edges of said walls and fastened thereto, a strip of metal located between spaced 20 edges of said walls out of contact therewith and fastened to said pieces, and a trim strip of thermal insulating material overlying edges of said walls and secured to said metal strip.

2. Refrigerator cabinet structure as set forth 25 in claim 1 in which said trim strip is secured to

said metal strip at points intermediate said resinous pieces.

3. Refrigerator cabinet structure as set forth in claim 1 in which said metal strip is formed with a crosswise corrugation intermediate its 5 points of fastening to said pieces to afford flexibility of the strip.

4. Refrigerator cabinet structure including inner and outer metal walls spaced apart to form heat insulation space therebetween, a plurality 10 of pieces of thermal insulation material located at intervals between the edges of said walls and fastened thereto, an elongated member located between spaced edges of said walls out of thermal contact therewith and fastened to said pieces, 15 and a trim strip of thermal insulating material overlying the edges of said walls and secured to said member at points intermediate said pieces.

5. Refrigerator cabinet structure as set forth in claim 4 in which said member is resilient and 20 formed with a corrugation intermediate points of fastening to said pieces to afford flexure of said member.

ALVAR LENNING. 25
